UNITED STATES PATENT OFFICE.

CARLOS WHITMORE, OF SAN FRANCISCO, CALIFORNIA, ASSIGNOR OF ONE-HALF TO JAMES H. BORLAND, OF SAME PLACE.

RAILWAY-RAIL JOINT.

SPECIFICATION forming part of Letters Patent No. 656,071, dated August 14, 1900.

Application filed March 27, 1899. Renewed May 8, 1900. Serial No. 15,980. (No model.)

To all whom it may concern:

Be it known that I, CARLOS WHITMORE, a citizen of the United States, residing at San Francisco, in the county of San Francisco and State of California, have invented certain new and useful Improvements in Railway-Rail Joints; and I do hereby declare the following to be a full, clear, and exact description of said invention, such as will enable others skilled in the art to which it most nearly appertains to make, use, and practice the same.

This invention relates to improvements in railway constructions, and more particularly to rail-joints; and it consists in the novel construction and arrangement of the parts, as hereinafter more fully set forth.

The objects sought to be accomplished are to provide a simple, rigid, and efficient joint 20 for the junction of the rails and to avoid the use of the usual bolts and nuts at present used with what is known as the "fish-plate" or "angle-plate."

In the drawings, Figure 1 is a plan view of 25 a rail-joint constructed and applied in accordance with this invention, showing the abutting ends of the rails in position. Fig. 2 is a cross-section on the lines X X, Fig. 3. Fig. 3 is a side elevation from the outside of 30 the rail.

In describing this invention with reference to the drawings distinguishing letters of reference will be assigned to the various parts. To the angle-plate supporting the base and 35 inside tread or flange side of the rail will be assigned the letter A, and to the angle-plate supporting the outside of the rail and engaging the base A' of the plate A the letter B. These common letters, strengthened by a number, will be assigned to the minor parts of 40 these groups.

The extension A' of the plate A extends around and under the base X' of the rail. The reinforcement A² under the juncture of 45 the abutting ends of the rails is added to increase the rigidity at this point.

When the angle-plate A and the rail X are in position as above described, the angle-plate B is set in position under the tread of the rail 50 and inclosing the web X' of the rail, as described in connection with the plate A.

Extending from the outer edge of the plate B downward and inclosing the edge of the plate A' is the extension B', which maintains the plate B in an upright position and holds 55 it to its work in connection with the lugs A³ and spikes C, which are driven to exert a strain inward against the plate B for this purpose. The lugs A³ are formed on the base A' of the plate A, and engage the beveled ends 60 of the plate B.

As disclosed by Fig. 1, the joint spans two ties—that is, one tie under each end thereof. The spike-holes A⁵ in the base-plate A' are thrown out of line with reference to the grain 65 of the tie to prevent splitting of the same and to better engage the plate B, which is made shorter than the plate A. The strengthening-bosses A⁴ and B³ are provided on the angle-plates at suitable distances for increased crushing strength. As disclosed in Fig. 2, the strengthening-boss A² is thrown slightly off center. This is to equalize the strains and to counteract the weakening effect of cutting in the plate A', as shown in Fig. 1, 70 to accommodate the plate B. The lugs A³ and the edges A⁶ of the cut-away portion of the base-plate A' form shoulders between which the plate B fits, thus preventing longitudinal movement of said plate, the projecting spike-heads holding said plate B against 75 sideways displacement.

In construction the whole joint is of malleable casting iron, consisting of the two parts A and B, no securing members other 85 than spikes being used to maintain the angle-plates in position. It has been found after the severest tests that this joint properly placed requires little or no attention until the perishing of the rail or tie. 90

In extreme climates where the expansion and contraction of the rails are considerable it may be found necessary to form a lug extending upward from the plate A' between the ends of the rail or some other such means to 95 prevent the rail ends creeping through the joint. This has been found in practice, however, unnecessary in all ordinary uses.

It is claimed that considerable expense can be saved by the use of this rail-joint, the 100 first cost being about the same or very little more than the usual fish-plate and bolts and

nuts; and, further, requiring less attention, a saving in the maintenance of way is accomplished.

The malleable casting of which the angle-
5 plates here used are formed being more rigid
than the wrought-iron fish-plates a more per-
fect and better-supported joint of the rail is
made, accomplishing a substantial saving in
wear and tear on the road-bed and rolling-
10 stock.

Having thus described this invention, it is
claimed—

A rail-joint comprising a plate adapted to
bear against one side of the rail, an extension
15 upon said plate adapted to extend under and
beyond the base of the rail, said extension

having lugs thereon, a second plate adapted
to bear against the rail on the side opposite
to that engaged by the first-mentioned plate,
and means for preventing vertical displace-
ment of the plates, the said second plate fit-
ting between the said lugs, whereby spikes
engaging the outer side of said second plate
will serve with the lugs to secure the said
second plate in position; substantially as de-
scribed. 20 25

In testimony whereof I have hereunto set
my hand this 16th day of February, 1899.

CARLOS WHITMORE.
